BY
her ATTORNEY

UNITED STATES PATENT OFFICE.

LOUIS STERN, OF NEW YORK, N. Y., ASSIGNOR TO UNDERWOOD AND UNDERWOOD, OF ARLINGTON, NEW JERSEY, A CORPORATION OF NEW JERSEY.

STEREOSCOPE.

1,197,679.

Specification of Letters Patent. Patented Sept. 12, 1916.

Application filed March 7, 1916. Serial No. 82,524.

To all whom it may concern:

Be it known that I, LOUIS STERN, a citizen of the United States, and a resident of the borough of Manhattan, city, county, and State of New York, have invented certain new and useful Improvements in Stereoscopes, of which the following is a full, clear, and exact description, such as will enable others skilled in the art to which it 10 appertains to make and use the same.

This invention relates to improvements in hand stereoscopes and more particularly to an improved "Scope" which can be folded into a complete package so that it may be 15 readily packed and stored to render it convenient for transportation.

One of the objects of my invention is to so construct and combine the hood and the picture holder that they may be folded upon 20 their common support and be fitted into each other so that they will be locked together for the purpose of forming a complete package.

Another object is to so construct the various parts that they may be quickly unfolded and will automatically resume their proper positions for use as a hand scope.

Other objects will appear from the herein-after description.

The invention will be fully understood 30 from the following description taken in connection with the accompanying drawings in which;

Figure 1 is a top plan view of the invention with portions of the folding hood shown broken away and partly in section. Fig. 2 is a sectional view on line 2—2 of Fig. 1. Fig. 3 is a section in detail of the hinged portion of the picture holder. Fig. 4 is a perspective view of an adjustable end 40 of the picture holder. Fig. 5 is an end elevation of the scope looking in the direction of the arrow 5 in Fig. 2. Fig. 6 is a perspective view of the scope folded and locked 45 into a package. Fig. 7 is a detail in perspective of the latch or locking bar, for the lens hood.

Referring to the drawings in which the same reference characters indicate the same 50 part in the several views; 10 is a rigid base piece preferably formed of aluminum having lugs 11 and 12 stamped up at each end, each lug being provided respectively with holes 13 and 13', to receive a small rod or 55 pintle 15 by means of which the hood H is

pivotedly attached and carried upon the base piece 10. A slot 14 is formed in the base piece 10 for the reception of a pin or stud 16 which forms one of the central pivots for a pair of levers 17 and 18 of the ordinary lazy tongs construction, as shown, one of the ends of said lazy tongs construction being pivoted at 19 and 19' to the sides of the base piece 10. The other end of the lazy tong construction is pivoted at 21 and 21' to a 60 base piece 20 to which base piece the picture holder P is hinged at 25, said holder being preferably formed of three parts 22, 23 and 24. The part 23 is provided with a back 65 26 and a bottom piece 27 extending at 70 right angles thereto, the edge of the bottom piece at 28 being utilized to form a portion of the hinged construction by means of which the picture holder is pivotally secured by a rod 25 to the base piece 20. The parts 75 22 and 24 are duplicates in reverse of each other and the construction is best described by reference to Fig. 4 which illustrates particularly the end piece 24. This end piece of the picture holder is adjustably secured 80 by pin and slot connection 30 and 31 and 32 and 33 to the side and bottom respectively of the main part of the pictureholder. The end piece 22 is similarly secured to the side and bottom of the main part of the pictureholder at 30' and 31', and 32' and 33'. A 85 spring 34 is mounted on the hinged rod 25 and co-acts with the picture holder P and the supporting base 20 so that the picture holder will be held by the spring in upright position when the scope is opened for use, and will also play its part in keeping the hood and holder together when these 90 parts are locked.

The hood H consists of a main piece 40 95 to which the lenses L are secured in any suitable way. The upper and lower shade portions of the hood 42 and 43 and the side shade portions 44 and 45 are hinged respectively to the top at 46, the bottom at 47 and the sides at 48 and 48' of the lens-holding portion 40. The top shade portion 42 is so shaped as shown that it will fit, as usual in such constructions, to the forehead of the user, and the bottom portion is likewise 100 shaped as shown so that it will fit the nose and cheeks of the user. The top or upper shade 42 is held normally open by a spring 50' secured to the pivot rod 50 of the upper hinge, and the lower portion of the shade is 110

held normally open by a spring 46 secured to the pivot rod 51 of the lower hinge. The side portions 44 and 45 are hinged by rods 52 and 52' extending through perforated lugs 53 and 53' and 54 and 54' at each outer corner of the lens holder. The upper and lower edges of the side portion 44 and 45 are provided with horizontal flanges 44', 44'', 45' and 45'' against which the edges of the upper and lower plates of the hood respectively impinge to hold said upper and lower portions in place when the scope is open for use. When the scope is folded, their flanges fit tightly over the upper and lower edges of the lens holding plate. The side portions 44 and 45 are so fitted to the lens holding plate that the outer edges 60 and 61 abut against the ends of the lens holding plate, which abutment prevents the said pieces from turning past the vertical.

A pivoted handle D of any approved type is secured to the underside of the supporting base 10. The particular form shown is that disclosed in Patent No. 1,157,419 granted to H. E. Richmond, October 19th, 1915, the handle of which is formed of a U-shaped spring rod 70 being pivotally attached at its upper end to projecting ears 73 which may be either stamped out of metal of the base plate 10 or formed from a separate plate 74 secured to the base plate 10. The notches 75 are provided in the projecting ears for holding the free ends 76 of the spring rod forming the handle in its upright position, the ears 73 serving to normally hold the handle in its horizontal position when folded against the under-side of the scope.

The lazy tongs support which consist of the levers pivoted to each other, as usual in such constructions, is so mounted that when opening and closing, one end of the lazy tongs will move and lie upon the upper surface of the base plate 10 to which the hood is pivoted while the other end of the lazy tongs will move and be adjacent to the under surface of the base plate 20 to which the picture holder is pivoted. The pivot pins 16 and 16' are fitted to slide respectively in slots 14 and 14' formed in the base plates 10 and 20. A handle h is fixed to the underside of the base plate 20 for convenience in opening and closing the lazy tongs.

70, 70', 71 and 71' are lips integral with the projections 90 and 90', which projections extend downwardly from the lens carrying plate. The lips form hinges with the projection at the outer edge of the base plate 10. The projections 90 and 90' impinge against the front edge of the plate 10 and hold the hood in an upright position against the pressure of the pivot spring when the scope is open for use.

The hood or lens carrying frame is held in place when in its upright position, against any pressure which may be brought upon it

by the head of the user, by means of the simple latch or coupler illustrated in Fig. 7.

A tube 80 is secured in any suitable way to the front edge of the base plate 10, the inside of the tube being so shaped as to securely fit and hold a rod 81 to which rod is secured a handle 82 which projects through a longitudinal slot 83 in the tube 80. At the ends of the rod 81, preferably rectangular but of any suitable shape in cross section, are secured coupling caps 84 and 84' each of which may be provided with lips 85 and 85' as shown to limit the movement of the coupler. It is therefore clearly seen that by means of this construction, when the lock is moved sidewise in one direction, the coupling pins 84 and 84' will be free from engagement with the projections 90 and 90' from the lens plate or carrier, and when the lock is moved sidewise in the opposite direction the coupling pins 84 and 84' will engage with the projections 90 and 90' thereby securely holding the lens plate in its upright position, and will prevent the hood from being turned on its hinges when in use due to pressure from the head of the user.

By means of the structure herein described, the scope may be folded into a package by turning on their pivots in the direction of the arrows 1 and 2 in Fig. 1, the upper and lower portions of the hood against the lens-holding plate, and then turning on their pivots in the direction of the arrows 3 and 4 in Fig. 1, the two side pieces of the hood against the upper and lower portions. The adjustable sides or ends of the picture holder are then moved outwardly and the picture holder and hood are respectively moved on their pivots down against the surface of the lazy tongs so that the hood and picture holder are both parallel to the lazy tongs, and the hood is in position to project into the picture holder. By closing the lazy tongs, the entire hood is shoved into the picture holder, the side portions of the picture holder are then pressed inward to embrace the ends of the hood thereby forming a neat compact package as shown in Fig. 6. The springs of the hinges for the hood and for the picture holder and also the springs for the hinges of the upper, lower and side shades of the hood all tend to force the parts into engagement one with the other so that the package is normally held by this spring pressure in its compact shape.

The different parts of the hood and picture holder are formed preferably of sheet aluminum, but obviously the material may be of any suitable metal or other rigid material, and are made by means of suitable dies so constructed that the different parts will be so pressed as to form the various hinged elements.

I preferably form a curve or bead of

metal at the outer edges of the plates of the hood at 49 and 49' which bear against and protect the face of the user.

It is apparent that changes may be made 5 without departing from the spirit or scope of my invention, and while I have shown certain features of my invention in the accompanying drawing, it is to be understood that said drawing is merely illustrative and 10 that I am not confined to what is there shown and herein described in connection therewith, except as may be specifically set forth in the claims.

Having now described my invention, what 15 I claim as new and desire to secure by Letters Patent, is:

1. In a stereoscope, a support, a lens frame, pivotally attached thereto, a picture holder also pivoted to the support, means 20 for moving the lens-frame and picture holder to and from each other and means for securing the lens-frame in the picture holder.

2. In a stereoscope, a pivoted hood, a 25 pivoted picture holder, means for connecting the hood to the picture holder, means for folding the hood and the picture holder respectively in horizontal positions, means for securing the hood in the picture holder 30 while in their respective folded positions.

3. In a stereoscope, a support, a lens-frame and a picture holder respectively pivoted thereto, means for normally holding the lens-frame and the picture holder in 35 parallel planes perpendicular to the support, means for securing the lens-frame and the picture holder one within the other parallel to the plane of the support.

4. In a stereoscope, a lazy tongs construction, a lens-frame and a picture holder pivoted at or near the respective ends thereof, and means for inclosing the lens-frame in 40 the picture holder upon contraction of the lazy tongs.

45 5. In a stereoscope, a hood, a support therefor, a spring operated pivot between the hood and support, a picture holder, a support therefor, a spring operated pivot between the picture holder and the support, 50 extensible means between the two supports, means for folding the hood and the picture holder in horizontal positions upon their respective supports, means for securing the hood within the picture holder on contraction of the extensible means.

6. In a stereoscope, in combination a hood provided with pivoted shades, a picture holder, an extensible connecting means between the hood and the holder, means for 55 holding the shades in position against the

body of the hood, and means for holding the hood, shades and picture holder in telescopic position against the body of the connecting means.

7. In a stereoscope, in combination a support, a hood pivoted thereto, a support, a picture holder pivoted thereto, shades pivoted to the lens part of the hood, an extensible connection between the two supports, means for holding the shades substantially parallel to the lens holder, and 65 the holder and shades in folded position inside of the picture holder.

8. In a stereoscope, a support, a collapsible hood pivoted thereto, a second support, a collapsible picture holder pivoted thereto, 70 extensible means connecting the two supports, means for positioning the hood and picture holder substantially in the same plane and means for drawing the collapsed 75 hood into the collapsed picture holder to form a compact package.

9. In a stereoscope, an extensible support, a hood provided with shades pivoted thereto, means for pivotally securing said hood to 80 an end of the extensible support, a picture holder, means for pivotally securing said holder to the opposite end of the said extensible support.

10. In a stereoscope, a lens holder, a support therefor, means for pivotally connecting the lens-holder to the support, a latch mounted on the support for securely holding the lens holder either in a vertical or 85 horizontal position.

11. In a stereoscope, a support, a collapsible hood pivotally secured thereto, a sliding latch, co-acting means on the latch and on the hood respectively to hold the hood either in a horizontal or vertical position.

12. In a stereoscope, a support, a lens holder, means for pivotally securing the one to the other, spring means normally holding the lens-holder in a vertical position, a sliding latch, means on the latch to engage the lens holder when the latch is moved in one direction, and to disengage the lens holder when the latch is moved in the opposite direction, and means for positively latching 100 the lens-holder either in a horizontal or vertical position.

In witness whereof I have hereunto set my hand at the borough of Manhattan, city and State of New York, this 24th day of February, 1916.

LOUIS STERN.

In presence of:—

ETHEL D. BARON,
ISABEL R. RICHARDS.
